UNITED STATES PATENT OFFICE.

HERBERT D. HOUGH, OF EDGEWOOD, RHODE ISLAND, ASSIGNOR TO WIGHTMAN & HOUGH COMPANY, OF PROVIDENCE, RHODE ISLAND, A CORPORATION OF RHODE ISLAND.

VANITY CASE.

Application filed March 30, 1923. Serial No. 628,745.

To all whom it may concern:

Be it known that I, HERBERT D. HOUGH, a citizen of the United States, residing at Edgewood, in the county of Providence and State of Rhode Island, have invented certain new and useful Improvements in Vanity Cases, of which the following is a specification.

This invention relates to an improved construction of a so-called vanity case and the like, employed more particularly for carrying toilet powder, rouge and a lip stick or other toilet preparations; and the invention has for its object to provide a deck plate supported in the casing having a recess adapted to carry one or more toilet preparations and also provided with a recess for the reception of a lip-stick holder, means being provided in the latter recess for permitting the holder to be tipped up so as to be readily engaged by the hand of the user.

A further object of the invention is the provision of an inwardly-rolled or turned edge on the body of the casing under which the corresponding edge of the deck plate is sprung or snapped to be removably locked in position in the casing.

With these and other objects in view, the invention consists of certain novel features of construction, as will be more fully described, and particularly pointed out in the appended claims.

In the accompanying drawings:

Figure 1 is a perspective view illustrating the body of a casing in which the three toilet preparations are carried also showing the lid of the casing in raised position.

Figure 2 is a plan view of the casing showing the lid raised and the recess formed in the deck-plate for the powder, also the recesses for the rouge and the lip-stick holder.

Figure 3 shows the construction of the bridge member in the lip-stick holder recess as being bent away to provide a recess at its end to permit the holder to be tipped up by pressing downward the unsupported end.

Figure 4 is a sectional elevation on line 4-4 of Figure 2.

Figure 5 is a perspective view of the deck plate showing two cup members and a recess therein also showing supporting legs which cooperate with the cup members to support the deck plate near the upper edge of the body of the receptacle.

Figure 6 is a perspective view of the lip stick holder.

It is found in the use of vanity cases of this character of advantage, to provide a deck plate having a recess or cup member therein for rouge, a second recess or cup for powder and a third transversely-disposed recess in this deck plate for the reception of a lip-stick holder, and to provide means in the holder recess whereby one end of this holder may be pressed downwardly thereinto, as illustrated in Figure 3, to raise its opposite end into position to be readily engaged by the hand of the user; also to provide an inwardly-rolled lip on the edge of the casing under which the edge of this deck plate may be snapped to be removably retained therein; and the following is a detailed description of my improved construction of vanity case which will accomplish the above desired objects:

With reference to the drawings, 10 designates the body of a casing to which one side is connected to a lid member 11 by a hinge 12. The inner face of this lid being preferably provided with a mirror 13.

In this body portion 10, I preferably mount a deck plate 14 preferably having a plurality of cups 15 and 16 set into openings therein, the upper edges of the cups being secured by solder or otherwise flush with the face of the deck plate. These cups are of such a depth that their bottom portions will rest against the bottom portion 17 of the body of the casing to assist in supporting this plate in position therein.

This plate is also provided with a third recessed portion 18 extending transversely thereof and is designed especially for the reception of the lip-stick holder 19. The stock of this recessed portion provides a saddle or support 20 for the holder and the middle portion of this saddle is pressed downwardly as at 21 to form a rib adapted to rest upon the bottom of the body for supporting the bridge against bending inwardly when pressure is brought upon the holder.

This bridge member is preferably of a length shorter than that of the holder providing a recess 22 at either end thereof, by which construction the unsupported end 24 of the holder may be pressed by the thumb of the user, into its recess 22 thereby lifting the opposite end of the holder as

shown in Figure 3, into position to be readily engaged or removed when desired. This saddle member also serves as a resilient connection between the main portion of the 5 deck plate and the rear portion 23 thereof. In order to hold or secure this deck plate in the body of the casing, I turn or roll the upper peripheral edge 24' of the body inwardly and I then snap the corresponding 10 edge 25 of the plate beneath this inturned edge of the body, the resiliency of the saddle member yielding to permit the snapping of the plate under the edge of the body, and its resiliency serves to assist in holding the 15 plate beneath this edge by spring pressure so that it will not be accidentally removed from its position when pressed into position.

This plate is preferably provided with a plurality of supporting legs 25 which cooperate with the cups 15 and 16 to support the 20 plate at its proper elevation in the body.

In these cup-shaped recesses 15 and 16 rouge and powder may be placed and powder puffs or pads 26 and 27 may also be deposited therein, which puffs are provided 25 with operating handles 28 and 29.

The device is extremely simple and inexpensive in construction and attractive in its appearance.

30 The foregoing description is directed solely towards the construction illustrated, but I desire it to be understood that I reserve the privilege of resorting to all the mechanical changes to which the device is 35 susceptible, the invention being defined and limited only by the terms of the appended claims.

I claim:

1. A vanity case having a body member and a lid, a deck plate in the body having recesses for the reception of toilet preparations and a lip stick holder, a saddle in one of the recesses for the lip-stick holder of a length less than that of said holder, and arranged to support the holder above the bottom of the body, whereby a downward pressure on one end of the holder will raise its opposite end from its saddle into position to be readily engaged. 40

2. A vanity case having a lid member and 50 a body member having its upper inner edge rolled in, a deck plate in the body snapped under said rolled-in edge, a cup for toilet preparation set into said plate and secured at its upper edges thereto, said cup being 55 of a depth to rest upon the bottom of said body and support said deck in position.

3. A vanity case having a body member and a lid, a deck plate in the body supported near its upper edge and having a recess 60 for the reception of a toilet preparation and also a recess for a lip-stick holder, a resilient saddle in said latter recess for supporting the holder above the bottom of the casing body and of a length to leave the 65 holder unsupported at its end whereby this end may be tipped down to raise its opposite end from its saddle, the peripheral edge of said body being turned inwardly under which the edge of the deck is snapped and 70 retained by the spring pressure of said saddle.

In testimony whereof I affix my signature.
HERBERT D. HOUGH.
